UNITED STATES PATENT OFFICE

JOSEPH KELLY, OF BOOTLE, ENGLAND

SHIP'S LIFE-SAVING APPARATUS

Application filed July 5, 1927, Serial No. 203,609, and in Great Britain July 10, 1926. Renewed February 10, 1930.

This invention has reference to the saving of life on shipboard, and has for its primary object to provide simple means or appliances whereby a buoyant or floatable structure may be readily and conveniently, and withall firmly, secured to a ship's deck, or the like, and rapidly detached or disconnected therefrom should occasion arise.

In the application of my invention to the provision of means for saving the lives of the crew of a submarine vessel if and when submerged and unable to rise to the surface of the water, I provide a chamber of suitable material, size and shape or configuration and slidably carry or support in opposite walls or sides—and preferably near the floor—thereof, rods or shafts of suitable diameter for the intended duty and of such length that a portion of each, exterior to the chamber, may be engaged with and so anchored to a bollard, bridle, bracket, or the like, fixedly secured to the deck of the vessel, whilst a portion of each rod or shaft extends into the interior of the chamber, so that said rods or shafts may be withdrawn or disconnected from their holding-down devices from within the chamber.

When the chamber is positioned by the means before described on the deck of a submarine vessel, a manhole provided in the former will be in alignment or register with a manhole provided in the deck of the latter, suitable provision being made for making and maintaining water-tight joints. Therefore, should the vessel when submerged be unable to rise, the crew will enter said chamber (in which there may be stored oxygen, rockets, food, et cetera) from the submarine vessel, and, after effecting water-tight closure of the manhole by means of a door or plate, will withdraw said rods or shafts from said exterior holding-down devices by means of suitable tackle which will ensure simultaneous release of the rods or shafts from the holding-down devices on the deck, so that said chamber with the occupants will be free to rise to the surface of the water.

Suitable stops may be provided on said adjustable rods or shafts in order to limit

and control the longitudinal movement of same through the sides or walls of the chamber, and the chamber apertures wherethrough said rods or shafts pass will be made watertight by means of suitably packed glands, or the like. A hermetically sealed belt, or compartment, or compartments, may be provided within or without said chamber in order to enhance the buoyancy thereof. 55

A conning tower of appropriate construction may be releasably secured to a submarine vessel in the manner hereinbefore described.

In the application of my invention to ships generally, an appropriately constructed house, or like structure is provided on a deck of the vessel and detachably anchored thereto, in the manner before described, being releasable, if desired, from the inside of the buoyant structure, or by projection of said rods or shafts inwardly from the outside of the structure. 65 70

Life-boats may also be detachably secured in position in the manner described.

In the accompanying sheets of explanatory drawings, there are illustrated, by way of examples only, various modes of carrying my invention into effect. 75

In said drawings:—

Fig. 1 is a longitudinal section, and Fig. 80 2 a part sectional plan, of a submarine vessel provided with a life-saving chamber embodying my invention.

Fig. 3 is a fragmentary section of a chamber of modified construction. 85

Figs. 4 and 5 are elevations, taken at right angles to each other, illustrating the application of my invention to the holding down of a ship's life-boat.

Figs. 6 and 7 are views of a steamship 90 and submarine vessel respectively, provided with my improvements.

In the several views like characters of reference denote like or equivalent parts wherever they occur. 95

Referring first to Figs. 1 and 2,

1 designates a steel chamber in opposite walls 1^a near the floor 1^b whereof are provided bearings 2 in which are slidably disposed rods or shafts 3. The outer portion of 100

each rod or shaft 3 is adapted to enter the eye 4 of a bridle, bracket, or other suitable holding-down device 5 which is secured to the deck 6 of a submarine vessel 7, whilst the inner end of the shaft 3 is pivotally connected at 8 to the lower end of a rod 9 which extends upwardly to and is connected with a shaft 10 revolubly mounted in bearings 11 provided at the upper end of chamber 1. Connected to each shaft 10 near the wall 1^c of chamber 1 is an end of a rod 12 to the inner ends of which rods are attached ends of a suitable flexible connection 13 which is led over a ring or eyelet 14 secured to the wall 1^c of the chamber and hangs downwardly as shown in Fig. 1. It will, therefore, be seen that by pulling said connection 13, with consequent operation of rods 12, shafts 10, and rods 9, said shafts 3 are simultaneously actuated, being moved inwardly, and withdrawn from engagement with the eyes 4 of brackets 5. Rubber washers 15 backed by stop nuts 16 are provided on the shafts 3 so that watertight sealing of the chamber is effected when the shafts are either in their projected or retracted positions.

A sunk portion 6^a of deck 6 of the submarine vessel 7 has a manhole 17 which may be closed by means of a hinged plate or cover 18 secured by swing bolts 19, a water-tight joint being effected by the packing ring 20.

Bolted to the upper face of said sunk portion 6^a and surrounding the manhole 17 thereof, is a flanged ring 21 the inner face whereof is screw-threaded, and bolted to the floor 1^b of the chamber 1 is a bush or sleeve 22, the interior whereof is screw-threaded.

Screwed through said bush or sleeve 22 and engaging the screw-threaded ring 21 is a tubular member 23 to the upper flanged portion 23^a whereof is pivotally connected a manhole cover 24 adapted to be secured by means of swing bolts 25.

26 denotes a water-tight joint-making packing ring located between the lower face of the flange 23^a of the tubular member 23 and the flange 22^a of the bush or sleeve 22; and 27 is a packing ring disposed between the manhole cover 24 and the upper face of the flange 23^a of tubular member 23.

The pitch of the screw-threading is preferably such that less than a full turn of the tubular member 23 will ensure its release from the screw ring 21 secured to the sunk deck portion 6^a of the submarine.

Should the submarine vessel become submerged and unable to rise to the surface of the water, the manhole covers 18 and 24 are opened—as indicated in dotted lines Fig. 1—so that the members of the crew may pass from the submarine vessel 7, through the manhole 17 and tubular member 23, into the chamber 1. If then the manhole cover 24 be closed and secured in a water-tight manner by swing bolts 25 and the tubular member

23 with manhole cover 24 be turned by means of a tommy bar 28 inserted in the flange 23^a to release the lower end of the tubular member 23 from the ring 21 and the flexible connection 13 pulled to withdraw shafts 3 from the eyes 4 of brackets 5, the chamber 1 with the persons in it becomes free to float off the submarine vessel and rise to the surface of the water, when manhole cover 29 provided with a water-tight joint-making packing ring 30, may be opened.

In the modification illustrated in Fig. 3 the chamber is composed of double walls having an air space 31 between same.

Referring to Figs. 4 and 5 of the drawings, there is shown a life-boat 32 which is detachably held on the curved deck of the vessel by means of slidable shafts 3 portions of which extend into the boat and are operated through rods 33 by means of a pivotal handle 34 to which said rods are connected. In order to facilitate the launching of the boat, there is provided an apron-like member 35 pivotally connected to the ship at 36. When the life-boat is to be launched, apron 35 is lowered by means of ropes 37 to the position shown in full lines Fig. 5, and the boat, which has slots 32 in the keel 39—wherein projecting members 40 of the apron 35 engage—is slid down the apron, being controlled by the tackle 41.

It will be seen that should the vessel take a list in the direction of the arrow (Fig. 5) the launching of the boat will not be interfered with or prevented.

In Fig. 6 the chamber,—adapted as a deck house—together with the life-boats 32 of the kind described with reference to Figs. 4 and 5, are shown fitted on the deck of a steamship 42.

In Fig. 7 the chamber is fitted on the deck 6 of the submarine vessel 7.

What I claim as my invention and desire to secure by Letters Patent is:—

1. In safety structures for ships, submarines and the like, wherein a buoyant carrier may receive and transport human life from the vessel when submerged, and wherein the buoyant carrier is normally mounted on the deck of the vessel, a buoyant carrier having its opposite side walls each carrying a rod-like member movable endwise within definite limits and adapted to prevent leakage of water into the carrier when in either extreme of its movement; means within the container for shifting said rod-like members concurrently, said means including rock-shafts and levers forming a unit individual to the respective rod-like members, and a connection for said units to provide concurrent movement of the units; individual members carried by the deck to receive the outer ends of the rod-like members when the latter are projected; and hatchway means operatively and detachably connecting the

carrier and vessel approximately central of the bottom of the carrier, said latter means including a tubular member permanently carried by the carrier and supporting the carrier hatchway cover, and a ring-member carried by the vessel, with said members complementally threaded for quick detachment, said tubular member forming the passageway between vessel and carrier, with the vessel 10 having a hatchway cover for the vessel end of the tubular member.

2. A structure as in claim 1 characterized in that the vessel has a depressed deck zone to receive the ring member of the hatchway means, the bottom of the carrier being substantially free from projections other than the tubular member, whereby the bottom wall of the carrier will normally rest upon the deck of the vessel.

20 In witness whereof I have signed this specification.

JOSEPH KELLY.
